UNITED STATES PATENT OFFICE.

ANDREW J. KNOPF, OF MAYWOOD, ILLINOIS.

DESIGN FOR A PLATE.

47,363.

Specification for Design.

Patented May 18, 1915.

Application filed November 10, 1914. Serial No. 871,406. Term of patent 3½ years.

To all whom it may concern:

Be it known that I, ANDREW J. KNOPF, a citizen of the United States, residing at Maywood, in the county of Cook and State of Illinois, have invented a new, original, and ornamental Design for Plates, of which the following is a specification, reference being had to the accompanying drawing, forming a part thereof.

I claim—

The ornamental design for a plate as shown.

ANDREW J. KNOPF.

Witnesses:

F. P. VEITH,
